CHAIR BACK

Philip M. Virtue, Los Angeles, Calif., assignor to Virtue Bros. Mfg. Co., Los Angeles, Calif., a corporation of California

Application April 29, 1950, Serial No. 9,574

Term of patent 14 years

(Cl. D15—8)

To all whom it may concern:

Be it known that I, Philip M. Virtue, a citizen of the United States, residing in Los Angeles, in the county of Los Angeles and State of California, have invented a new, original, and ornamental Design for a Chair Back, of which the following is a specification, reference being had to the accompanying drawing, forming part thereof:

Fig. 1 is a perspective view of a chair back, showing my new design.

Fig. 2 is an enlarged top plan view thereof.

Fig. 3 is a similarly enlarged front elevational view.

I claim:

The ornamental design for a chair back, substantially as shown.

PHILIP M. VIRTUE.
